(57) **CLAIM**

The ornamental design for a cuff for a hot melt adhesive hose, as shown and described.

DESCRIPTION

FIG. 1 is a front perspective view of the cuff for a hot melt adhesive hose according to the present invention.

FIG. 2 is a rear perspective view of the cuff for a hot melt adhesive hose according to the present invention.

FIG. 3 is a left side view of the cuff for a hot melt adhesive hose according to the present invention.

FIG. 4 is a right side view of the cuff for a hot melt adhesive hose according to the present invention.

FIG. 5 is a front view of the cuff for a hot melt adhesive hose according to the present invention.

FIG. 6 is a rear view of the cuff for a hot melt adhesive hose according to the present invention.

FIG. 7 is a top view of the cuff for a hot melt adhesive hose according to the present invention; and,

FIG. 8 is a bottom view of the cuff for a hot melt adhesive hose according to the present invention.

The broken lines define unclaimed boundaries of the design.

1 Claim, 5 Drawing Sheets
